N° 979.

*David Hathaway's Design for a Stove Door;
Assigned to Messrs. Fuller, Warren & Morrison, Troy, N.Y.*

Patented Jan'y. 12. 1858.

Des. 979

David Hathaway of Troy N.Y.
Assignor to
Fuller Warren & Morrison of same place.
Letters Patent No. 979, Dated Jan 12th 1858.

The schedule referred to in these Letters Patent and making part of the same.

To all whom it may concern:

Be it known that I, David Hathaway, of the city of Troy, in the County of Rensselaer, and State of New York, have invented or produced a new and Original Design for a Door of a Cooking Stove; and do hereby declare that the following is a full & exact description of the same reference being had by letters to the annexed photographic drawing making a part of this Specification.

My new ornamental design for a door of a Cooking Stove consists of a collection of the ornamented Δ shaped, raised portions, a, arranged together upon the plate in the particular manner shown in the photograph, - surrounded by the ornamental border b.

What I claim as my invention or production & desire to secure by Letters Patent is the ornamental design for a door and of a cooking Stove herein described and shown in the annexed G.M.P photographic drawing
